(No Model.)

H. D. ADELL.
ELEVATOR SHAFT CLOSING MECHANISM.

No. 555,670.

Patented Mar. 3, 1896.

UNITED STATES PATENT OFFICE.

HENRY D. ADELL, OF COLUMBUS, OHIO.

ELEVATOR-SHAFT-CLOSING MECHANISM.

SPECIFICATION forming part of Letters Patent No. 555,670, dated March 3, 1896.

Application filed August 28, 1895. Serial No. 560,761. (No model.)

To all whom it may concern:

Be it known that I, HENRY D. ADELL, a citizen of the United States, residing at Columbus, in the county of Franklin and State of Ohio, have invented a certain new and useful Improvement in Elevator-Shaft-Closing Mechanism, of which the following is a specification.

My invention relates to the improvement of elevator-shaft fire-doors, and the objects of my invention are to provide improved means for closing elevator-shaft floor-openings and provide other improvements, the details of construction of which will be more fully pointed out hereinafter. These objects I accomplish in the manner illustrated in the accompanying drawings, in which—

Figure 1 is a vertical section of an elevator-shaft having my improvements therein. Fig. 2 is a detail view in perspective illustrating the upper portion of the shaft-framework and means for supporting and operating the latches. Fig. 3 is a transverse section on line xx of Fig. 1; and Fig. 4 is a sectional view through one of the springs which I employ, as hereinafter described.

Similar letters refer to similar parts throughout the several views.

a represents the various floors of a building 30 through which are formed, as is usual, elevator passage-ways a' . b represents the usual oppositely-located vertical elevator-car guide-posts which are arranged to project within the shaftway on opposite sides thereof in the usual manner.

Arranged on opposite sides of the forward portions of the elevator-shaft are vertical standards b' , and a similar standard b^2 is supported at the rear of said shaft. Between 40 each of the floors I pivot at oppositely-located points on the standards b' and b^2 corresponding ends of latch or catch fingers b^3 , the outer ends of the latter having hook-shaped terminations, as shown. As indicated more clearly in Fig. 2 of the drawings, the upper end ends of the posts b' are connected by a transverse frame-bar b^4 , from the center of the length of which leads rearwardly a frame-arm b^5 , the outer end of the latter connecting with

50 the upper side of the post b^2 . Upon the upper side and at each end of the bar b^4 is journaled a pulley c , and a similar pulley c' is

journaled on the outer end portion of the frame-arm b^5 .

d represents an endless rope or cable, which 55 passes over the pulleys c , thence down on the outer sides of the frame-posts b' through suitable openings in the floors a . Beneath the lower floor a of the building the rope d passes about two oppositely-located pulleys d' , which 60 are supported from a cellar-floor e . The rope d at a point between the upper pulleys c , has connected therewith one end of a rope d^3 , the latter extending rearwardly, passing over the pulley c' , thence extending downward adjacent to the post b^2 , and having its lower end 65 connected through the medium of a coil-spring d^4 with the cellar-floor board e .

With the center of the length of each of the latches b^3 of the side posts b' is connected 70 one end of a short cord f , the remaining end of which connects with the rope d at a point above the latch. Through the medium of short cords f' the latches b^3 of the post b^2 are in a similar manner connected with the 75 cord d^3 . These short cords f and f' are designed to normally suspend the latches b^3 in inwardly-projecting and horizontal positions, as shown in the drawings.

The cords f on one side of the shaft are, as 80 shown, made to run over small pulleys f^3 , which are suspended from the post b' on the corresponding side of the shaft.

g represents doors, one of which has its rear side hinged to the rear side of the elevator-shaft opposite each of the floors, said door 85 g being designed to cover the rear half of said elevator-shaft when supported horizontally, as hereinafter described and as shown in Fig. 3 of the drawings. The remaining portion 90 of the shaft-opening at each floor is adapted to be covered by two oppositely-located and hinged door-sections g' . The edges of these door-sections g' when elevated to a substantially vertical position are adapted to 95 engage with the hook ends of the side latches b^3 , while the rear doors g are adapted to be similarly retained in a vertical position by engagement with the rear latches b^3 of the posts b^2 .

h represents a circular metallic casing, which is provided on its rear side with an attaching-flange h' , and which is provided in its periphery on its forward side with an open-

ing h^2 . Through the center of this casing h passes a pin h^3 and about said pin and at a distance therefrom is arranged a winding-drum h^4 . i represents a coil-spring which is contained in said winding-drum, one end of said spring being connected, as indicated, with the drum and the remaining end with the pin h' . To the outer side of the drum is fixed the inner end of a flexible cord or strip k , which is wound upon the drum and the outer end of which passes outward through the opening h^2 of the casing. One of these spring-cases which, as will readily be seen, is substantially of the construction employed in producing the well-known form of spring-actuated tape-measures, is secured to the inner side of each of the posts b' and b^2 at a point above each of the doors g' and g . The tension of the springs i contained in the casings h , while it is such as to assist in the elevation of the doors to a vertical position, is not sufficient to raise said doors without additional force.

On each of the floors a adjacent to the elevator-shaft I provide a substantially vertical spring-strip m , the lower end of the latter being secured to the floor and the upper portion of said spring-strip being provided with a slight inward bow against which the adjoining shaft-door is adapted to bear when elevated to a vertical position.

o represents an elevator-car, which may be of any of the well-known forms, and which is adapted to be raised and lowered within the shaft in the usual manner. This elevator-car is provided on its upper side and on opposite sides of its top portion with rollers p , which are journaled in suitable brackets. The elevator-top is also provided with an upwardly-bowed spring-strip q .

The operation of opening and closing my improved elevator-shaft doors is substantially as follows: On the first up trip of the elevator-car in the morning the closed doors g' and g are opened by contact with the under sides thereof of the car-top strip or bumper q , and said doors are further raised to a vertical position by contact with the rollers p , which project from opposite sides of the car. In thus raising the doors to vertical positions their upper edges are caused to engage, respectively, with the hooked ends of the latches b^3 , the latter thus serving to retain said doors in their open positions. After the doors have thus been opened it is evident that the passageway through the shaft will remain open until it is desired to close the same, which may be readily accomplished by a downward pull on the rope d on that side of the shaft on which the pulleys f^3 are employed to cause a disengagement of the latches with the door edges.

This disengagement of the latches and doors, as will readily be seen, is effected by lifting said latches through the medium of the connected ropes d and d^3 . In dropping to their closed positions the doors are prevented from descending too rapidly and to an undesirable depth by the pulling action of the spring-actuated supporting-strips k . It is evident that these supporting-strips are taken up on the drum h^4 of the casing h when said doors are open.

The spring-strips m are so arranged as to make sufficient pressure against the doors when the latter are raised to overcome any tendency of the doors to remain in the vertical position after the latches are released therefrom. It will be observed that the inner edge of the door g is provided with a central recess s , through which the usual car-supporting cable s' may pass. As indicated in Fig. 1 of the drawings, I connect the cellar-floor beneath the elevator-shaft with the cord d by means of a coil-spring t , the latter serving to normally retain the rope in such position as to hold the latches b^3 horizontally.

From the construction and operation herein shown and described it will be seen that means are provided for automatically opening the doors of an elevator-shaft and that improved means are provided for retaining the doors in an open position and closing said doors when desired.

Having now fully described my invention, what I claim, and desire to secure by Letters Patent, is—

In an elevator-shaft the combination with the shaft and its framework, hinged doors g and g' adapted to close said shaft at each floor of a building, a spring-actuated reel supported on the elevator-framework above each of said doors and cords connecting said doors and reels and adapted to wind upon the latter, of vertical frame side posts b' and rear posts b^2 , latches pivoted as described to said posts between the floors, pulleys c and c' journaled above said posts, pulleys d' journaled below said elevator-shaft, an endless rope d passing over said pulleys c and d' , cords f connecting said endless rope and latches b^3 , said cords f passing over pulleys f^3 on one side of the shaft and a cord d^3 leading from the rope d over the pulley c' , the lower end of said cord having a spring connection with a stationary frame-base beneath the elevator-shaft and cords f' connecting the latches of the post b^2 with said rope d^3 , substantially as and for the purpose specified.

HENRY D. ADELL.
